MILTON H. SHOENBERG, OF SAN FRANCISCO, CALIFORNIA.

SAFETY-SWITCH.

1,393,322.

Specification of Letters Patent.

Patented Oct. 11, 1921.

Application filed December 27, 1919. Serial No. 347,732.

To all whom it may concern:

Be it known that I, MILTON H. SHOENBERG, a citizen of the United States, and a resident of the city and county of San Francisco, State of California, have invented new and useful Improvements in Safety-Switches, of which the following is a specification.

My invention has for its object the automatic interruption of an electric circuit, when the current flowing in the apparatus and supplied through my safety switch for any reason exceeds a predetermined amount, and at the same time, the switch may be closed or opened manually, but in the event of such closure the circuit will be immediately automatically interrupted in the event of this excess flow of current; furthermore, it is impossible with my invention to retain 20 the flow of current beyond the limits of safety by any possible hand manipulation of the switch.

These objects I attain by providing a movable switch blade, or blades, which may be swung into either of two extreme positions under the action of a snap spring from a suitable finger member, and in either of its extreme positions the switch is "open" while in its intermediate position the movable switch member completes the circuit, and while in such position is under the control of an expansion element or thermostat wire in series with the flowing current.

The current which is caused to flow upon the closure of the switch and flowing through the thermostat wire raises the temperature thereof, results in the expansion of the wire, which operates the aforesaid latch, releasing the switch member from its intermediate position, and causing it to snap in one or the other direction, depending upon the position of the finger member. These extreme positions corresponding with the open positions of the switch result in the interruption of the current flow.

It is to be specially noted that the "make and break" at the switch contacts always occur very quickly and under the action of a spring, protecting the parts against discharge damage. Furthermore, as the expansion of the thermostat element is exactly coincident with the temperature raise of the said element, the switch is instantly and automatically opened by any excess current within extremely wide range without damage to the parts, and the terminal ap-

paratus in circuit with the switch of my invention is adequately protected against any overload.

By referring to the accompanying drawings my invention will be made clear.

Figure 1 is an enlarged view of my switch arranged in conjunction with the standard form of socket. The housing is not shown in the figures as it is well known in the art and forms no part of my invention.

Fig. 2 is a side view at right angles to Fig. 1 and to a reduced scale.

Fig. 3 is a side view similar to Fig. 2 but from the opposite side thereof.

Fig. 4 is a side view similar to Fig. 2, except that the finger piece and switch blade is shown in a different position.

Fig. 5 is the same as Fig. 2 and Fig. 4, except the switch blade and finger piece are shown in another position.

Fig. 6 is a diagram of the connections thereto.

Fig. 7 is a cross section through the insulated base and socket showing the thermostat element therein.

Fig. 8 is a detail showing of the latch 21 and its electrical connections and associated parts.

Throughout the figures like numerals refer to similar parts.

The switch parts are mounted on an insulated member indicated by the numeral 1, supported on a suitable base 2, carrying also a connecting piece or standard socket 3.

At 4 is a U shaped member carried upon the supporting pivot 5, which pivot passes through enlarged holes 6, 6 of the switch blade 15, and on the end of the said pivot I mount the operating finger piece or key 9. The movement of the key 9 causes a corresponding movement of the U member 4. This latter is perforated on its end for the passage of the bar 10, which bar is pivoted at 11 to the second U member 12, to which is rigidly attached the side arms 13, 14 with which are mounted the switch blades 15, 16 through insulated connections 17, 17, 17, 17 so that the members 15 and 16 are preferably insulated from the balance of the switch structure, except when in contact with circuit terminals.

Around the bar 10 is assembled the coil spring 18 under compression, which acts upon the second U piece 12, to cause it and the corresponding switch blades 15, 16 to swing in one direction or the other depending upon

- the position of the U piece 4, and therefore upon the operation of the key or finger piece 9. It will be obvious that if the U piece 4 be turned into its "up" position, the spring 18 will tend to throw the switch blades to one extreme or limit, and if the U piece 4 be turned into the down position the spring will tend to throw the switch blades to the opposite limit.
- 5 10 The limits of said movement are either the surface 19 or 20, or the latch member 21, the latter serving as limit of movement only for the switch blades when the U piece 4 is turned to its upper position. The said latch 15 21 is under the control of an expansion element, or thermostat wire 22 (see Fig. 7) which wire terminates in the button 23, and is held in tension by the coil spring 24.
- 20 Coöperating with the latch 21 is a light spring 25, lightly holding the said latch against the button 23. I prefer to connect the button 23 with the circuit terminal 31 by the flexible strip 27 to insure an electrical connection.
- 25 30 The upper part of the switch blade 16 I provide with a tongue, or projecting lug 28, adapted to engage with the said latch 21 when the thermostat wire 22 is in its contracted position admitting of the latch engaging the said lug. The main circuit wires are connected to terminals 29, 30 from which the current is conveyed upon the closing of the switch and the engagement of the switch blade at 28 with the latch 21 through the 35 switch blades 16 and 15, piece 27 and wire 22, by which the current is conveyed to the socket and button 26, the other leg being connected to the socket shell 3 through a connection 33, and contact terminal 32.
- 40 45 The operation is as follows: Assuming that a lamp of normal wattage, for which the apparatus has been previously designed and constructed, be connected into the socket 3, and that the switch parts are 50 in the position shown in Fig. 5, the key 9 is now to be turned so that the U piece 4 is forced downward into the position shown in Fig. 4, which will result in the switch blades 15, 16 turning into the position there shown, during which the projecting lug 28 will have passed under the tripping end of the latch 21. The key is now turned back in the opposite or "on" direction when the U piece 4 is turned into the position indicated in 55 Fig. 2; this will cause the switch blades 15, 16 to snap into the position there shown, and to be retained in such position by the latch 21 during normal current consumption. Current will now flow to the lamp socket 60 and the lamp will be energized, the current therefor flowing also through the wire 22 in series therewith. Said current is not, however, sufficient to heat the wire 22 and expand it beyond the predetermined range, and consequently latch 21 is not raised sufficiently to release the lug 28 of the switch blades. The light may be turned on and off as often as required by merely shifting the key 9 when the switch blades will occupy the position of closed in Fig. 2, or open in Fig. 70 4, as the case may be. Should, however, a short circuit occur, or any load in excess of that for which the thermostat wire and switch have been calibrated, said excess current flowing through the wire 22 will cause 75 its expansion to a degree sufficient to raise the latch 21, through the extension of the coil spring 24, from its contact with the switch blade lug 28, enabling the switch blades 15, 16 to "snap" into the position 80 indicated in Fig. 5.
- Reference is herein made to my co-pending application Serial No. 347,734, filed December 27, 1919, wherein is set forth a further showing of certain features of my invention.
- Claims.
1. In an electrical safety switch, an oscillating member adapted to snap about a central pivot into each of two extreme positions 90 under the action of a spring, a spring constructed and adapted to cause said movement on either side of said pivotal means on a reverse movement of the opposite end of said spring, contacting blades constructed 95 and adapted to engage said member when the member is in its intermediate position, said blades constructed and adapted to complete a circuit through the blades and the member, latch means adapted to retain the member in said intermediate position when swinging from one end of its range of movement, associated means controlling said latch adapted to actuate to release the said latch upon an excess of current flowing 105 through said blades and switch member.
2. In an electrical safety switch, an oscillating member adapted to snap about a central pivot into each of two extreme positions 110 under the action of a spring, a spring constructed and adapted to cause said movement on either side of said pivotal means on a reverse movement of the opposite end of said spring, contacting blades constructed 115 and adapted to engage said member when the member is in its intermediate position, said blades constructed and adapted to complete a circuit through the blades and the member, latch means adapted to retain the member in said intermediate position when swinging from one end of its range of movement, associated means controlling said latch adapted to actuate to release the said latch upon an excess of current flowing 120 through said blades and switch member, including an expansible element in series with 125 said blades and member adapted to expand upon the excess of current flowing there-

through and releasing said latch whereby the member snaps into open circuit position under the action of the spring.

3. In an electrical safety switch, an oscillating member adapted to snap about a central pivot into each of two extreme positions under the action of a spring, a spring constructed and adapted to cause said movement on either side of said pivotal means
- 10 on a reverse movement of the opposite end of said spring, contacting blades constructed and adapted to engage said member when the member is in its intermediate position, said blades constructed and adapted to complete a circuit through the blades and the member, latch means adapted to retain the member in said intermediate position when swinging from one end of its range of movement, associated means controlling said
- 15 latch adapted to actuate to release the said latch upon an excess of current flowing through said blades and switch member, including an expansible element in series with said blades and member adapted to expand upon the excess of current flowing there- through and releasing said latch whereby the member snaps into open circuit position under the action of the spring, said expansible element secured to a supporting frame
- 20 on the end opposite to said latch.
- 25 4. In an electrical safety switch, an oscillating member adapted to snap about a central pivot into each of two extreme positions

under the action of a spring, a spring constructed and adapted to cause said movement on either side of said pivotal means 35 on a reverse movement of the opposite end of said spring, contacting blades constructed and adapted to engage said member when the member is in its intermediate position, 40 said blades constructed and adapted to complete a circuit through the blades and the member, latch means adapted to retain the member in said intermediate position when swinging from one end of its range of movement, associated means controlling said 45 latch adapted to actuate to release the said latch upon an excess of current flowing through said blades and switch member, including an expansible element in series with 50 said blades and member adapted to expand upon the excess of current flowing there- through and releasing said latch whereby the member snaps into open circuit position under the action of the spring, said expansible element secured to a supporting frame 55 on the end opposite to said latch, and a spring adapted to force the tension of said expansible wire, and a button at the termina- tion of said wire, and a relatively lighter 60 spring retaining said latch in contact with said button.

In testimony whereof, I have hereunto set my hand at the city and county of San Francisco, State of California.

MILTON H. SHOENBERG.
